UNITED STATES PATENT OFFICE.

EMIL F. LEWIS FRITZ, OF CHICAGO, ILLINOIS.

GARMENT.

Application filed September 30, 1922. Serial No. 591,627.

To all whom it may concern:

Be it known that I, EMIL F. LEWIS FRITZ, a citizen of the United States, and a resident of the city of Chicago, county of Cook, and 5 State of Illinois, have invented certain new and useful Improvements in Garments, of which the following is a specification.

My invention relates to novel improvements in garments, and has for its principal 10 object the provision of an improved construction which will be highly efficient in use and economical in manufacture.

Among the salient objects of the invention is the provision of a garment, of the corset 15 type, having body covering members formed of pliable metallic material, such as aluminum or the like, which, when worn, will retain the contour of the body, and be easily adjusted and fitted around the body and be 20 comfortable to wear.

Other objects will appear hereinafter.

The invention consists in the combinations and arrangements of parts hereinafter described and claimed.

25 The invention will be best understood by reference to the accompanying drawings forming a part of this specification, and in which,

Fig. 1 is an elevational view of a garment 30 embodying the invention;

Fig. 2 is a top edge view, of the same; and

Fig. 3 is a fragmentary sectional detail view, of the same, taken substantially on line 3—3 of Fig. 1.

35 In carrying the objects of the invention into effect, my improved garment comprises a plurality of sections, namely, an abdomen covering section 5 having a plurality of tapes 6 on its opposite side edges, the abdomen covering portion 5 is preferably formed 40 of pliable metallic material such as aluminum, or the like, and in this instance is formed with a plurality of perforations 7. The tapes 6 are secured preferably to elastic hip covering portions 8 and 9 adapted 45 to cover the body portion of the wearer slightly above the hips, the tapes 6 being provided with push buttons 9' of any approved type. The hip covering portions 50 are detachably secured to back covering portions 10 and 11 preferably formed in substantially the same way and of the same material as the abdomen covering portion 5.

The back covering portions 10 and 11 are 55 also provided with tapes 12 carrying push

buttons 9' through the medium of which these portions are detachably secured to the hip covering portions. The back portions 10 and 11 are provided adjacent the outer side edges with grommets 13 through which 60 laces of the usual form pass when the garment is mounted to embrace the body of the wearer. The metallic covering portions of the garment are preferably formed with slightly rolled edges as at 5' Fig. 1. 65

The object of perforating the portions 5, 10 and 11 is primarily to provide ventilation when the garment is positioned around the body.

The curvature of the top and bottom edges 70 of the garment is of a shape commonly known in the art of manufacturing a garment of this type and is to be of such shape that the garment can be comfortably worn.

While I have specified that the garment is 75 secured around the body of the wearer through the medium of laces it is to be understood that snap-fast buttons of the usual construction well known in the art may be used inasmuch as the garment is adjustable through the medium of the elastic 80 hip covering portion of the garment.

The garment will not only be comfortable 85 to wear but will be the principal agent in retaining the contour of the body of the wearer in its proper shape without being detrimental to the wearer as it is preferable that the material forming the body covering portions be formed of such pliable material 90 that will be durable and permit easy movement of the body.

While I have illustrated and described the preferred form of construction for carrying 95 my invention into effect, this is capable of variation and modification without departing from the spirit of the invention. I, therefore, do not wish to be limited to the precise details of construction set forth, but desire to avail myself of such variations and modifications as come within the scope of 100 the appended claim.

Having described my invention what I claim as new and desire to secure by Letters Patent is:

A garment of the class described including 105 a front body covering portion formed of pliable metallic material and having ventilating perforations formed therein, side body covering portions formed of elastic material, connections comprising tapes 110

fixedly secured to the side body covering portions and detachably secured to the front body covering portion, a back body covering portion including parts formed of pliable metallic material having ventilating perforations formed therein and having grommets formed therein affording means of lacing the parts together, and connections comprising tapes fixedly secured to the side body

covering portions and detachably secured to the back body covering portions. 10

In testimony whereof I have signed my name to this specification in the presence of a subscribing witness.

E. F. LEWIS FRITZ.
